FIG.1

FIG.4

FIG.2

FIG.3

FIG. 5

FIG. 6

FIG. 7

FIG. 8

FIG. 1 is a perspective view of the antenna, showing my new design, as seen from a position to one side and somewhat forwardly of the antenna, the flat bottom portion being plain and the bottom curved wall being tapered and plain;

FIG. 2 is a side elevational view showing the opposite side from that shown in FIG. 1;

FIG. 3 is a top plan view of the antenna of FIG. 2;

FIG. 4 is a rear elevational view thereof from the left of FIG. 2;

FIG. 5 is a front elevational view thereof from the right of FIG. 2;

FIG. 6 is a perspective view, similar to FIG. 1, showing a modified form of the antenna, the front view thereof being substantially the same as FIG. 5, and the bottom wall being curved;

FIG. 7 is a side elevational view of the opposite side thereof; and

FIG. 8 is a top plan view showing the rear surface thereof.

The dominant features of my new design are shown in solid lines, in the drawings.

I claim:

The ornamental design for an antenna, substantially as shown and described.
